UNITED STATES PATENT OFFICE.

FREDRICK BEIERMEISTER, JR., OF TROY, NEW YORK.

BUTTON-HOLE.

SPECIFICATION forming part of Letters Patent No. 291,486, dated January 8, 1884.

Application filed June 13, 1883. (No model.)

To all whom it may concern:

Be it known that I, F. BEIERMEISTER, Jr., a resident of the city of Troy, in the county of Rensselaer and State of New York, have invented certain new and useful Improvements 5 in Button-Holes; and I do hereby declare that the following is a full, clear, and exact description of the invention, that will enable others skilled in the art to which it appertains to make 10 and use the same, reference being had to the accompanying drawings, and to the letters of reference marked thereon, which form a part of this specification.

Similar letters refer to similar parts in the 15 several figures therein.

My invention relates to improvements in button-holes for collars, cuffs, and wearing-apparel in general; and it consists in providing an elongated button-hole with a stay-piece 20 to vary its utilized length.

The object of my invention is to provide in wearing-apparel button-holes that will permit of adjusting a garment to different sizes.

Figure 1 is a plan view, showing my improved button-hole applied to one end of a collar. Fig. 2 is a plan view of same collar end with stay-piece removed. Fig. 3 is a plan view of same, showing the loose end of the stay folded back upon the body of the stay. 30 Fig. 4 is a plan view of the stay detached from the collar.

Many garments adapted to receive or be attached to other garments by means of buttons are made and supplied to the trade in sizes. 35 This is a special feature in shirts, collars, and cuffs. The sizes vary by half an inch—that is, a No. 15 collar is fifteen inches long, and the next larger size is No. 15½, which is fifteen and one-half inches long, and the next smaller size 40 is No. 14½, which is fourteen and one-half inches long. It frequently happens that a shirt neckband or collar will stretch or shrink in laundering, and a collar which once fitted a certain sized shirt will not fit after being 45 laundered. It is either too long or too short. It is very desirable, therefore, that both the shirt and the collar should be adjustable as to length. It is for the same reason desirable that detachable cuffs and shirt wristbands 50 should be adjustable as to length. I am able

to provide the desired adjustability by means of my improved button-hole.

In Fig. 2 of the drawings, C represents an elongated button-hole in the end of a collar-band; and, in Fig. 4, G represents a stay-piece 55 provided with a slit, H. The stay-piece is stitched or otherwise attached to the collar-band, as shown by the dotted lines J in Fig. 1, and in such a position that the slit H corresponds with one end of the button-hole C. 60 The slit and button-hole may be button-hole stitched together through the stay and collar-band, so that the slit is integral with that part of the button-hole. The stay is also stitched transversely to the band and at a point about 65 midway between the two ends of the button-hole C, so as to leave a loose end, I, of the stay. The other end of the collar-band is provided with a button-hole and stay-piece, G, made in the same manner. When it is desired to wear 70 the collar at its smaller size, the parts are left as shown in Fig. 1, and the button inserted through the stay; but, if the larger size is desired, the loose end I of the stay is turned or folded over upon the stay, as shown in Fig. 3, 75 and the button inserted in the other end of button-hole C without passing through the stay. Thus two different sizes are obtained in the same collar, and the resisting-points, as well as every portion of the button-holes, are 80 in the same line of draft, which permits of a narrow band, and does not affect the set or fit of the collar, except in size or length. The stay-piece may be of any desired shape or material, provided it is stitched or attached to 85 the goods on both sides of button-hole C, so as to divide the latter in two parts, and be folded from one part toward or upon the other. The slit H may extend any desired distance 90 beyond the transverse row of stitching shown in Fig. 1 as passing through its end into the loose part I of the stay, as it need not extend so far as said row of stitching.

I have shown the button-hole somewhat exaggerated in size for the purpose of illustration, and in such a way that the variation in size would be more than one trade size; but any desired amount of variation can be produced. For example, if we wished to construct a collar which could be varied by one- 95 100

half a size, or one-fourth of an inch in length, we would extend the loose end I, Fig. 1, of the stay out over the button-hole C, and extend the slit H in the same direction until its 5 eyelet or resisting end is within one-eighth of an inch of the resisting end of the button-hole C. Then, by releasing attaching-button from the stay-piece, folding the stay-piece back, and inserting the button in the eyelet end of the 10 button-hole C, the length of the collar would be varied just one-fourth of an inch—one-eighth of an inch at each end—or one-half a trade size. It is evident, therefore, that the stay piece or attachment may be constructed to vary the 15 size of a garment from one size to another, or by any fractional part of a size.

The attachment may be formed from one or more of the band-plies, or may be inserted at its fixed end between the plies.

20 I am aware that neckbands of shirts and analogous articles have been made with button-holes in different vertical planes to adapt them to wearers' necks and wrists of different sizes. This is not my invention, broadly, as my improvement consists more especially in the novel 25 means for accomplishing the result hereinbefore stated. Therefore

What I claim as new, and desire to secure by Letters Patent, is—

1. An attachment for the button-hole end of 30 a collar or other wearing article, consisting of a short stay-piece formed with a horizontal slit of a size to receive a collar-button, or the like, and of a length less than the collar-button hole, substantially as set forth.

35 2. The combination, with a collar or other wearing article formed with an elongated button-hole of a short stay-piece formed with a horizontal slit of a size to receive a collar-button, or the like, and of a length less than the 40 said button-hole, and fastened on opposite sides of the button-hole and at points lying between straight lines of the respective ends of the said button-hole, substantially as shown, and for the purposes set forth.

45 In testimony whereof I have hereunto set my hand this 11th day of June, 1883.

FREDRICK BEIERMEISTER, JR.
